CHIKAYOSHI NAKATSU, OF KUMAMOTO-SHI, JAPAN.

COAL WASHING AND SELECTING APPARATUS.

Application filed March 1, 1926. Serial No. 91,539.

My invention relates to improvements in coal washing and selecting apparatus, and has for its object to provide an apparatus of the class specified which is simple in construction and effective in operation.

Another object of my invention is to provide an apparatus of the character specified which permits an automatic washing and selecting operation of coal by a simple operation of the up and down motion of a piston acting on a body of water.

Another object of my invention is to provide an apparatus of the character specified having a cylindrical washing drum which facilitates the uniform distribution of pressure throughout the whole body of water within which the washing and selecting actions are effected.

Another object of my invention is to provide means whereby the washing and selecting apparatus is constructed with a minimum amount of material, the parts being arranged so as not to decrease the strength thereof.

A further object of my invention is to provide a piston structure whereby the operation of the piston does not cause any unfavorable disturbance of the coal treated.

A further object of my invention is to provide means whereby the coal selected can readily be taken from the selecting drum.

A still further object of my invention is to obtain means whereby the stroke and speed of the piston and the number of revolutions of the wings adapted to expel the coal selected can be regulated in accordance with the quality of the coal to be treated.

A still further object of my invention is to provide means which permits of the expelling of the various qualities of coal selected through independent discharging ports corresponding to the quality of the selected coal.

Other objects and particularities of my invention will be made clear by reference to the following description and the accompanying drawings wherein:

Fig. 1 is a vertical section of a coal washing and selecting apparatus embodying my invention.

Fig. 2 is a plan view of the same.

Fig. 3 is a vertical section of the cylindrical drum shown in Fig. 1.

Fig. 4 is a vertical sectional view of the piston room.

Referring now more particularly to the drawings, my apparatus comprises a select-

ing drum 1 of a substantially cylindrical form having a bottom 2 of a conical form. Intermediate the depth of the drum 1 is provided a partition 3 having a number of holes, the partition also being a conical form with its center portion forming the apex of the cone. A cylindrical tube 4 is arranged centrally through the drum 1 and the partition 3, a cover 5 being arranged on the top while the lower end opens to the exterior.

The wall of tube 4 has a plurality of slate discharging apertures 6 above the central portion of the partition 3 and these apertures are adapted to be shut and opened by a suitable plunger 7 which is operated by a handle 8 through a link 9. The tube 4 has a plurality of other slate discharging apertures 10 opening into the bottom portion of the drum 1.

The apparatus also comprises a piston chamber 11 communicating with the lower compartment of the drum below the partition 3, and supplied with water through a port 12 which is in communication with a suitable water supply, not shown.

A piston 13 operates in the chamber 11 and is provided with spring flap valves 14 on the under surface, co-operating with corresponding ports 15 in the piston. The piston is actuated or reciprocated within the chamber 11 by means of eccentric rods 16 connected to a counter shaft 17 driven by a suitable motor through a pulley 18.

The counter shaft 17 carries another pulley 19 which drives a second counter shaft 20 through a belt and a pulley.

The shaft 20 carries a bevel wheel 22 which engages another bevel wheel 23 carried by a vertical journal shaft 24 extending into the top portion of the drum 1 through a cover member 25 thereof.

The journal shaft carries a plurality of wings 26 each of which takes the form of an involute curve and rotates with the shaft in the top portion of the drum 1, so as to move the coals to the outer side of the drum and from the central portion thereof a gate 27 is provided in the drum below the level of the wings 26, and controlled by means of a link 28 and a rotary handle 29.

A discharge outlet 30 is provided in the wall of the drum 1 above the level of the wings 26 opening into the drum and communicating with the exterior through which good selected coal is passed. Inasmuch as the lower wing 26 is shorter than the upper wing, good coal is gradually selected while

being washed and is carried from the central part to the outer part of the drum while the upper and longer wing serves the same purpose and in addition acts to drive the good 5 quality coal through the coal outlet 30.

In operation, coal to be treated is fed through a suitable opening provided in the cover 25 into the drum 1 over the partition 3, and water is fed into the drum through the 10 port 12. The shaft 17 is driven by a driving motor, not shown.

The piston 13 reciprocates within the chamber 11 and periodically presses and releases the water contained in the drum 1.

15 Slate and coal of a small size drops through the holes of perforated partition 3 into the conical bottom of the drum and are discharged or expelled through the openings 10 and then the tube 4 to the exterior.

20 Above the partition 3, the coal of medium or large size is subjected to the periodical up and down action of the water and by the aid of the floating action of the water the coal of good quality having less density is 25 floated on the upper layer, while the coal of worse quality having heavier density is caused to sink down.

20 The wings 26, which are preferably rotated at a speed of one fifth to one seventh the stroke of the piston gather up the coal of best quality which is discharged through the outlet 30 to the exterior, while the coal of medium quality is gathered and discharged through the gate opening 27. The 35 very heavy coal is discharged to the exterior through the apertures 6 and the tube 4.

As the discharge of the coal accompanies the expelling of water, the port 12 must continuously feed the water required to enable 40 the washing and selecting operation of the apparatus.

45 As previously disclosed, the piston 13 is provided with spring valves 14, there is no trouble of drafting the coal over the partition 3 through the holes thereof when the piston is in its backward stroke.

It must also be noted that the bottom of the drum has a conical shape which facilitates the uniform propagation of water pres-

sure and also the gathering and discharging 50 of the slate and fine coal. The conical form of the partition 3 also effects a similar function.

The drum 1 has substantially a cylindrical form and it will be obvious that the structure can be the lightest in comparison to a predetermined water pressure and also facilitate a uniform propagation of the water 55 and the pressure thereof.

Although I have illustrated only one example of the invention, it will be obvious to those skilled in the art that various modifications and changes may be made without departing from the spirit and scope of the 60 invention.

Having now particularly described the invention what I claim is:

In a coal washing and selecting apparatus, a selecting drum having a conical bottom, a conical perforated partition in said drum dividing the same into compartments, the upper compartment of the drum having a selected coal outlet, a cylindrical tube arranged vertically in the drum and provided with slate discharging apertures positioned 70 adjacent the partition and the bottom, a plunger valve operating in the tube, a rod arranged through the top of the drum, a tubular shaft surrounding the rod and terminating short of the tube, a pair of horizontal 75 wings carried by the shaft and disposed one above the other and each being in the form of an involute curve, the lower wing being shorter than the upper wing so that coal is gradually selected while being washed and 80 carried from the central part to the outer part of the drum while the upper and longer wing serves the same purpose as the lower wing and in addition acts to finally drive the good selected coal through the coal outlet 85 in the upper part of the drum, and the conical shape of the partition and the bottom of the drum facilitating the delivery of slate through the apertures into the tube, substantially as and for the purposes set 90 forth.

In testimony whereof I affix my signature.

CHIKAYOSHI NAKATSU.
